Primary Examiner — Stacia Cadmus*(74) Attorney, Agent, or Firm* — Flynn, Thiel, Boutell & Tanis, P.C.(57) **CLAIM**

The ornamental design for a wheel, as shown and described.

DESCRIPTION

FIG. 1 is a perspective view of a wheel of the present invention;

FIG. 2 is another perspective view thereof;

FIG. 3 is a left side view of the wheel of the present invention, with the right side view being a mirror image thereof; and,

FIG. 4 is a cross-sectional view of the wheel of the present invention taken along line IV-IV of FIG. 3.

The broken line showing of the wheel and the tire is included for the purpose of illustrating environment and forms no part of the claimed design. The dash-dot-dash broken lines define the bounds of the claimed design and form no part thereof.
